UNITED STATES PATENT OFFICE.

WILLIAM SELLERS PICKERING AND HARRY GROVE, OF EXETER, ENGLAND.

CENTER VALVE FOR GAS-PURIFIERS.

SPECIFICATION forming part of Letters Patent No. 761,993, dated June 7, 1904.

Application filed April 1, 1904. Serial No. 201,166. (No model.)

To all whom it may concern:

Be it known that we, WILLIAM SELLERS PICKERING, a resident of 4 School road, St. Thomas, Exeter, and HARRY GROVE, a resident of Ivydene, Pinhoe road, Exeter, in the county of Devon, England, citizens of Great Britain, have invented certain new and useful Improvements in and Relating to Center Valves for Gas-Purifiers, of which the following is a specification.

This invention relates to a valve for gas-purifiers, and particularly to a valve for gas-purifiers on the ground, which valve is capable of being mounted on the side of the purifier-casing and is capable of use in units for any number of purifier-compartments.

According to the invention a valve-casing *a* is provided in which the respective parts are to be put together in units, each unit consisting of an upstanding pipe and a hood and a transverse passage above the pipe and hood and partitions between each unit, so as thus to form a chamber between the upstanding pipe and the partitions within which water or other liquid may be admitted and within which a hydraulic seal may be formed by the hood on the liquid rising above the lower edge thereof.

The invention is illustrated in the accompanying drawings, in which—

Figures 1, 2, and 3 are respectively sectional elevation, sectional plan, and sectional side elevation, of a valve applicable for two purifiers on the ground, which valve is attached to the side of the purifier-casing.

In carrying the invention into effect the main inlet-pipe *b* is connected to the respective inlet-compartments *c' c'*, the connecting-pipe being in continuation of the upstanding pipes *c' c'*, respectively, while the main outlet-conduit *c* is connected to the respective outlet-compartments *d' d'*, the connecting-pipe being in continuation of the upstanding pipes *d' d'*, respectively.

Each unit of the valve-casing is formed of a base part *u*, a top part *v*, a transverse partition *w* and intermediate vertical partitions *t*, and terminal covers *x x'*.

The lower part *u* of the casing forms the bottom of each compartment and is provided

with a vertical flange *u'*, by means of which the valve-casing is secured to the purifier-casing and similarly a horizontal flange *u''* at its upper part receiving a similar flange *v'*, provided upon the upper part *v* of the valve-casing, which latter is also provided at its opposite side with a vertical flange *v'*, by means of which it is secured to the purifier-casing. The horizontal partitions *w* are connected to the respective vertical partitions, as well as to the side of the purifier-casing, as illustrated.

The inlets and outlets to and from the compartments of the purifier are advantageously situated immediately beneath the horizontal partition aforesaid, from which depend the hoods *f*, which surround the inlet and outlet pipes *c'* and *d'*, respectively.

Each partition *t* is provided with a slot *t'* toward its upper part corresponding to the space formed between the top of the valve-casing and the horizontal partition aforesaid, so that thus the top of the valve-casing and the horizontal partition forms a conduit *r*, through which the gas may flow from one end of the valve-casing to the other.

The two middle compartments—*i. e.*, the inlet-compartment *c'* and the outlet-compartment *d'*—communicate through an aperture *t'*, formed at the lower end of the central vertical partition *t*, these respective compartments being completed by vertical partitions *x x* on each side of the central partition *t*, while the terminal inlet-chamber at one end and the terminal outlet-chamber at the other end communicate by the conduit *r* before referred to.

An additional water seal is provided at the terminal outlet-chamber by the provision of the partition *a'*, which is secured by its upper and lateral flanges to the side of the valve-casing and purifier-casing, respectively, and to the end of the horizontal partition before referred to.

It will be understood that when neither of the compartments of the purifier are to be cut out the unpurified gas passing through the first upstanding pipe *c'* to the right would enter the first purifier-compartment through the slot *c'* and after passing through the compartment return into the next outlet-compartment.

ment through the slot d^3 . The outlet-compartment d' is sealed, and the gases will thus be compelled to pass through the slot t' at the lower end of the vertical partition t , which divides the outlet-compartment d' from the inlet-compartment e' , thence passing into the second inlet-compartment e' through the slot e^3 into the second compartment of the purifier, whence the gas returns again through the slot d^3 into the next outlet-compartment d' . The second inlet-compartment e' will be flooded, while the second outlet-compartment d' will be free of water; but the end compartment controlling the conduit r will be flooded, so that thus the gas is compelled to pass through the second outlet-pipe into the outlet-main. In the same way it will be understood that the one or other, or both, compartments of the purifier may be cut out from the circuit of the gases as may be required in working, whereby the purifying material may be renewed.

What we claim as our invention, and desire to secure by Letters Patent, is—

1. In a valve for gas-purifiers a plurality of pairs of inlet and outlet chambers having pas-

sages near their upper ends for communicating with a gas-purifier, an inlet-pipe extending upwardly into each inlet-compartment, an outlet-pipe leading away from each outlet-compartment and liquid-seal passages placing the inlet and outlet chamber of each pair in communication, substantially as described.

2. In a valve for gas-purifiers, a plurality of pairs of inlet and outlet chambers having passages at their upper ends for communicating with a gas-purifier, a hooded inlet-pipe extending upwardly into each inlet-compartment, a hooded outlet-pipe extending upwardly into each outlet compartment and passage placing the lower parts of the inlet and outlet chambers of each pair in communication whereby said passages may be closed by a liquid seal, substantially as described.

In testimony whereof we have signed our names to this specification in the presence of two subscribing witnesses.

WILLIAM SELLERS PICKERING,
HARRY GROVE.
